NILS HARALD WENER, OF STOCKHOLM, SWEDEN, ASSIGNOR TO SVENSKA AKTIE-BOLAGET MONO, OF STOCKHOLM, SWEDEN.

GAS-ANALYZING APPARATUS.

1,326,814.

Specification of Letters Patent. Patented Dec. 30, 1919.

Application filed July 30, 1918. Serial No. 247,416.

To all whom it may concern:

Be it known that I, NILS HARALD WENER, civil engineer, subject of the King of Sweden, residing at 11 Uppsala-gatan, Stockholm, Sweden, have invented certain new and useful Improvements in Gas-Analyzing Apparatus, of which the following is a specification.

The present invention relates to improvements in gas-analyzing apparatus which are worked by pressure above or below atmospheric, and in which during the operation a certain action, as for instance the reversing of a cock, the opening or closing of a valve, the starting of a registering device and so on is intended to take place. Such actions are particularly required in gas analyzing apparatus, in which two or more analyses of different kinds are to be carried out successively and alternately.

The purpose of the invention is automatically and in a very simple manner to bring about an action of the kind above described, for instance the regular adjusting of the analyzing apparatus for analyses of one or the other kind.

The invention consists in that the said action is effected directly or indirectly by means of the changing pressure of the pumping device of the apparatus, or the pressure of the conduit leading to the primary measuring-vessel. A piping, preferably in parallel with the pressure-piping connected with the apparatus, leads to a pressure-chamber of one kind or another, where the pressure is caused to effect motion and this motion is then utilized for effecting the action wanted.

For instance in case of an apparatus of the kind above described, *i. e.* an apparatus by means of which two or more analyses of different kinds are to be effected a cock or the like is used which alternately connects the pumping-device to one or the other gas analyzing apparatus and which is operated by a piston movable in a cylinder which in its turn is connected with the pressure-pipe leading to the pump.

In the accompanying drawing Figures 1, 2 and 3 show schematically three embodiments of the invention. Figs. 1 and 2 show an arrangement in which the driving pumping-device is connected with two gas-analyzing apparatus, and Fig. 3 shows an

arrangement with only a single gas-analyzing apparatus. 55

In Fig. 1 P indicates a pump worked by a pressure fluid and containing mercury and which may be constructed for instance according to the German Patent No. 226,542 60 being provided with two vessels *a* and *b* communicating with each other through an opening *c*. In the inner vessel *b* the ascending pipe *d* is arranged which opens into the vessel *e*. From this vessel a return-pipe *f* 65 leads to the tube *g*. The gas-analyzing apparatus are connected in a known manner with the pipe *g*. In the drawing *M*¹ and *M*² are the two primary measuring-vessels of these gas-analyzing apparatus. 70

The vessel *b* communicates through the pipe *h* and the pressure-reducing-valve *i* with the pressure fluid working the pump *P*, said fluid being obtained from a source not shown. 75

As known, the working of the pump depends upon the increase of pressure in the vessel *b*, whereby the mercury in this vessel is pressed higher and higher in the ascending pipe *d*. At the same time the mercury 80 rises in all vessels and tubes connected with the pipe *g*, thereby discharging samples to the gas-analyzing apparatus.

At last the mercury in the ascending pipe *d* reaches the upper opening of the same 85 and as soon as a small part of the mercury has been ejected the whole column which now becomes shorter and shorter and therefore lighter and lighter is forced out of the pipe *d*. This ejected mercury flows through 90 the return pipe *f* back to the tube *g*. After a period a reduction of pressure takes place when the free spaces of the vessels *a* and *b* are put in communication with the atmosphere through the pipe *d*, and the pump *P* 95 will then again be filled with mercury. At last the surface of the mercury has risen so high that a part of the mercury can flow through the opening *c* into the vessel *d*, and now the pumping device is again put in action, as the free connection with the atmosphere is again shut off. 100

In this way, as may be seen, a falling and rising of the liquid column and also a corresponding change of the pressure prevailing in the system will be effected. One of these changes is, according to the invention, utilized for reversing the cock *h*. 105

According to Fig. 1 the increase of pressure as well as the variation of the mercury level in the vessel *b* are utilized for the reversing of the cock *k*. In the vessel *b* 5 a contact bar *l* is arranged, the lower end of which enters into the mercury, when the surface of the same stands in its uppermost position. This contact bar is connected through a wire *m* and source of current *o* with one end of the winding of an electromagnet *n* the other end of which is connected with the mercury in the vessel *a*. The armature *p* of the electromagnet is provided with a nose *q* coöperating with a 10 counter-nose *r* of a reciprocating bar *s*. This bar is provided with a pawl *t* coöperating with the ratchet-wheel *u*. The latter is fastened to a shaft *v* which also carries the cock *k*. The bar *s* is further connected 15 with a piston *w* movable in a cylinder *x* which cylinder is connected by means of a pipe *y* with the pipe *h*. *z* indicates a spring which tends to displace the bar *s* to the left.

25 The mode of operation is as follows: When the pressure in the pipes *h* and *y* increases, the piston *w* will be displaced to the right against the action of the spring *z*. The spring is then put under pressure and 30 the different parts take the positions shown in the drawing. As soon as the vessel *b* is put in communication with the atmospherical air, atmospherical pressure will prevail in the pipe *y* and also in the cylinder *x*, while a displacement of the bar *s* to the 35 left is at first prevented by the nose *q*. In a short time, however, the surface of mercury in *a* will come into contact with the contact bar *l* whereby the electric circuit is closed. The armature *p* is then 40 attracted, so that the bar *s* is freed and is moved to the left by the spring *z*, whereby the ratchet wheel *u* and consequently also the cock are operated. Now the reversal has 45 taken place and the pump will then operate the second of the two gas analyzing apparatus. In this way, consequently, one or the other apparatus will be operated alternately.

50 In the same manner three or more apparatus may be successively put in and out of operation.

Fig. 2 shows another embodiment of the 55 reversing device in which no electric circuit is employed. The piston *w* acts upon a double lever 2 swinging on the shaft *v* and provided with a pawl 3 coöperating with the ratchet-wheel *u*. A spring 4 is supposed to hold this lever 2 in the position shown. 60 The pipe *y* is provided with a branch 5, leading to a cylinder 6 the piston of which is connected with a slipper 8. 9 indicates a pawl-lever, swingably mounted on a shaft 10 and held in the position shown by a 65 spring 11. The one end of the pawl-lever

9 carries a push-roller 12, coöperating with the slipper 8, and the other end is provided with a pawl 13, arranged in the path of a projection 14 of the lever 2.

The mode of operation of the device is 70 the following: When the pressure increases in the pipes *h*, *v* and 5, at first the releasing device is put into action. The piston 7 rises and the slipper 8, when passing the roller 12, pushes the same backward, so 75 that the pawl-lever 9 is moved and the lever 2 is released. The spring 4 then causes this lever to swing whereby the wheel *u* and, consequently, also the cock *k* (Fig. 1) is 80 operated. In a short time the pressure has risen to such a degree that the piston *w* will be lifted. The spring 4 is thereby put under tension, until at last the lever 2 is caught by the pawl-lever 9 and held fast. At this moment the maximum pressure is reached 85 and the pump is released so that the over-pressure in the pipes *y* and 5 ceases. The piston 7 then sinks down to its end-position in which the slipper 8 is not in contact with the push-roller 12, and the same course of 90 operation may then begin again.

It is obvious that the parts may be adjusted in such a manner that the release can take place at any pressure and even on reaching the maximum pressure. For example, in the 95 embodiment shown in Fig. 1, the contact bar 1 may be positioned at any desired height. If, for instance, it is not wanted to effect every second analysis in one and every second in the other apparatus, but to analyze 100 for a certain time in one apparatus and then in the other, the release of the lever 9 may be effected by means of a clock-work.

Fig. 3 shows an embodiment which is simplified in that a single measuring-vessel is 105 used which is connected alternately to the two gas-pipes. *a* indicates the pump-vessel continually fed with water through the pipe 15. 16 is a siphon which opens into the vessel *a* and through which the vessel *a* is 110 emptied when the maximum pressure is reached. 17 is a tube leading to a certain pressure-vessel 18. From the liquid-space of this vessel the pipes 19 and 21 rise which both lead in a known manner to the absorption-receptacle 19 through the measuring-vessel *M*¹ and the pipe 20.

The pipe 22 opens at one side into the measuring-vessel *M*¹ through a liquid-seal 21¹ and at the other side into the chest of a 120 three-way cock 23. The two other ways of this cock are connected through the pipes 24 and 25 with the gas-pipes *P*¹ and *P*². The plug of the cock 23 is arranged on a shaft 26 which carries a ratchet-wheel 27 coöperating 125 with a shifting bar 28, arranged on a piston 29. The cylinder 30, in which this piston moves, is connected by means of a pipe 31 with the vessels *a* and 18.

The mode of operation of this pumping- 130

device does not essentially differ from that of the device shown in Fig. 1. The siphon 16 acts in the same manner as the return pipe f in Fig. 1. When the fixed pressure is obtained, the wheel 27 and the shaft 26 are operated, so that the pipe 22 is alternately connected with P^1 and P^2 .

It is obvious, that this device is very simple. It is, however, to be observed, that in an arrangement with only one measuring-vessel the inconvenience arises that at each analysis a remainder of gas from the foregoing analysis will be mixed with the new quantity of gas.

15 It is obvious that the arrangement according to Fig. 3 can be combined with a pumping device according to Fig. 1.

In most gas analyzing apparatus the diagram is obtained by means of a clock-work. 20 According to the invention, however, it is also possible to obtain the diagram by means of the pressure above or below atmospheric.

We claim:

1. In an apparatus of the class described, 25 the combination with a plurality of gas-sampling receptacles, of a fluid pressure pump common to said sampling receptacles and operating by intermittent pressure within the system, a valve for opening communication between said pump and each of said sampling receptacles in rotation, and means responsive to the fluctuations of pressure within the system for actuating said valve.

2. In a device such as is set forth in claim

1, means for constantly supplying a pressure medium to the pump, a pumping liquid in the pump acted upon by said pressure medium, whereby pressure is accumulated, means for periodically relieving the pressure, and a pressure responsive device in 35 communication with the pressure medium for actuating the valve between the pump and the sampling receptacles.

3. In a device such as is set forth in claim 2, means whereby the pressure medium 45 causes a surging back and forth of the pumping liquid, means for controlling the valve actuating means, and means actuated by the movement of the pumping liquid for actuating said controlling means.

4. A device such as is set forth in claim 3, 50 in which the pumping liquid comprises a conductor of electricity and the means for actuating said controlling means comprises an electromagnet, and a contact member in 55 circuit with the coil of said electromagnet and positioned above the pumping liquid, and having a portion which is above the lowest level but below the highest level of said liquid, whereby said portion is alternately 60 immersed in and freed from said liquid, and said circuit is alternately closed and opened.

In testimony whereof I affix my signature in presence of two witnesses.

NILS HARALD WENER.
